UNITED STATES PATENT OFFICE.

JOSEPH W. DAWSON, OF ST. LOUIS, MISSOURI.

ATTACHMENT FOR MOTOR BOATS.

Application filed December 4, 1924. Serial No. 753,792.

To all whom it may concern:

Be it known that I, JOSEPH W. DAWSON, a citizen of the United States of America, a resident of the city of St. Louis, in the 5 State of Missouri, have invented certain new and useful Improvements in Attachments for Motor Boats, of which the following is a full, clear, and exact description, reference being had to the accompanying 10 drawing, forming a part of this specification.

This invention relates to attachments for motor boats, and particularly to a device which may be associated with a motor boat 15 whereby said motor boat may be operated at a very low rate of speed.

As is well known, most motors of the type used to propel row boats and canoes are capable of operating at a single rate of speed. 20 This speed may, of course, be varied slightly by manipulating the fuel throttle of the motor, but there are no speed-changing mechanisms associated with these motors as there are with other types of motors. It is often 25 desirable, for instance in fishing with a trolling line where said line is drawn slowly through the water, to operate the boat at a very low rate of speed, and the main object of the present invention is to produce 30 a simple and inexpensive device which may be attached to a boat and which will permit of said boat being operated at a very low rate of speed.

With the foregoing and other objects in 35 view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications 40 which come within the scope of the claims hereunto appended.

Fig. I is a side elevation of a motor of the 45 outboard type used to propel row boats and canoes, a fragment of a boat or canoe being associated with said motor and said motor being equipped with my improved attachment.

Fig. II is a perspective of my improved attachment.

Fig. III is a fragmentary view, partly in 55 elevation and partly in section, showing the adjusting mechanism of my improved attachment.

In the drawing, A designates a fragment of a row boat or canoe to the rear wall of which is attached by means of clamping devices B a motor C of the outboard type. 60 The motor C illustrated in Fig. I does not form a part of my invention, as the attachment forming the subject matter of this application may be associated with any motor of the outboard type, and for this reason 65 the particular motor illustrated will not be described in detail. All that need be known for the present purpose is that means is provided to impart rotary motion to the propeller D associated with the boat. 70

The motor illustrated in Fig. I, like most motors of its type, is not provided with speed-changing mechanism whereby great changes in the speed at which the boat may be driven may be attained. On the other 75 hand, the only way in which changes in the speed of the boat may be attained with the motor illustrated is by regulating the flow of fuel to said motor. It is apparent that variance in the speed of the boat obtained 80 in this manner would necessarily be very slight and that the motor could not be throttled down sufficiently to cause the boat to move at the slow speed necessary for trolling. 85

With the foregoing in mind, I have provided the motor illustrated in Fig. I with an attachment which comprises a supporting element E composed of a pair of plates 1 and 2. The plates 1 and 2 are provided 90 with semicircular openings and have semicircular flanges 3 and 4 arranged adjacent to said semicircular openings, as shown clearly in Fig. II. The plates 1 and 2 are also provided with integrally formed lugs 95 5 and 6 through which clamping devices 7, preferably in the form of screws, are passed to clamp said plates 1 and 2 together. By referring to Fig. I it will be seen that the plates 1 and 2 are associated 100 with the standard S of the motor C in such manner that the semicircular flanges 3 and 4 on said plates 1 and 2 embrace said standard S, said semicircular flanges forming a complete annular flange when they are 105 associated with each other which annular flange surrounds said standard, and said semicircular flanges being drawn into close frictional contact with said standard by the clamping screws 7. It is plain from the foregoing that when the plates 1 and 2 are 110 secured together about the standard S in the

manner described, the supporting element E is very firmly secured to said standard.

8 designates a plate which is hingedly secured to the supporting element E, said plate being provided with a pair of extensions 9, each of which supports an inwardly extending pivot pin 10. Formed at the outer end of the plate 1 is a pair of members 11, circular in cross section, each of which is provided with an angularly arranged recess 12 into which the pivot pins 10 of the plate 8 are extended. It will be seen by referring to Fig. III that the recesses 12 are closed at their lowermost ends 15 and open at their upper ends, and that said recesses incline downwardly from their open upper ends. It is plain from this that when the pivot pins 10 are extended into the recesses 12 the plate 8 will be pivotally supported by the supporting element E, it being plain also that when it is desired to remove the plate 8 from the supporting element E said plate need only be moved to an elevated position, when the pivot pins 25 10 may be moved out of the recesses 12 by moving the plate 8 upwardly and rearwardly.

Formed at the forward end of the plate 1 is a portion 13 having a curved face in 30 which is formed a plurality of apertures 14, and formed integral with the plate 8 is an internally threaded lug 15 through which a screw 16 passes. As will be seen by referring to the drawing, the screw 16 is capable of being adjusted toward and away from the curved face of the portion 13 and Fig. III shows that the screw 16 is provided with a reduced inner end portion which may be extended to any one of the apertures 14. The 40 plate 8 is provided with a cutout portion 17 into which the portion 13 on the plate 1 extends, and it is apparent, in view of this, that said plate 8 may swing relative to the supporting element E. It is likewise plain that the plate 8 may be maintained in various positions relative to the supporting element E by causing the reduced end portion of the screw 16 to be extended into the various apertures 14.

50 The plate 1 is provided with a rib 18 and the plate 8 with ribs 19 and 20 to give the required rigidity to said plates.

In the use of my improved device the 55 plate 8 is arranged adjacent to the propeller D of the boat. The plate 8 is hingedly supported by the supporting element E, as already explained, and it may be moved toward and away from the propeller so that more or less surface of said plate may be 60 exposed to the body of water which is being cast rearwardly by the propeller. The positioning of the plate 8 adjacent to the propeller has the effect of retarding the speed 65 of the boat, for the reason that the body of water being cast rearwardly strikes the

plate 8 and therefore tends to interfere with the forward movement of said plate, and because said plate is secured to the boat the speed of said boat is thereby decreased. Also, the plate 8 acts as a drag in the 70 water, and this interferes with the progress of the boat. It is apparent that by exposing more or less of the surface of the plate 8 to the body of water being cast rearwardly by the propeller, the speed of the boat may 75 be regulated.

When desired the plate 8 may be entirely removed from the supporting element E by simply unscrewing the screw 16 and withdrawing the pivot pins 10 from the recesses 12.

I claim:

1. An attachment for a motor boat, comprising a pivoted plate arranged immediately behind and extended transversely of the propeller of the motor boat, said plate being hinged at the top to permit the lower end thereof to swing upwardly and downwardly, and means comprising an adjusting screw whereby the position of said plate with respect to said propeller may be regulated. 85

2. An attachment for a motor boat, comprising a plate arranged in close proximity to the propeller of the boat, a supporting element above said propeller by means of which said plate is pivotally supported, and means whereby the position of said plate may be regulated, said means comprising a portion on said supporting element provided with a plurality of apertures, and an adjustable member on said plate adapted to be moved into and out of the various apertures. 95

3. An attachment for a motor boat, comprising a plate arranged in close proximity to the propeller of the motor boat, a supporting element above said propeller by means of which said plate is pivotally supported, and means whereby the position of said plate may be regulated, said means comprising a portion on said supporting element provided with a plurality of apertures and an adjusting screw supported by said plate and adapted to be moved into and out of various apertures. 100

4. An attachment for a boat provided with a motor having a standard, comprising a plate arranged immediately behind and extended transversely of the propeller of the boat, a supporting element adapted to be clamped to said standard, said plate being pivotally attached to said supporting element in a manner to permit the lower end thereof to swing upwardly and downwardly, and means whereby the position of said plate with respect to said propeller may be regulated. 115

5. An attachment for a boat provided with a motor having a standard, comprising a plate arranged in close proximity to the propeller of the boat, a supporting element 120

formed of a plurality of parts adapted to be clamped together to secure said supporting element to said standard, said supporting element being provided with recesses 5 into which pivot pins associated with said plate extend whereby said plate is pivotally supported by said supporting element, and means whereby the position of said plate with respect to said propeller may be regu- lated, said means comprising a portion on 10 said supporting element provided with apertures, and an adjusting screw associated with said plate adapted to be extended into various apertures to maintain said plate in different positions. 15

In testimony that I claim the foregoing I hereunto affix my signature.

JOSEPH W. DAWSON.
